United States Patent

Des. 236,978
Patented Sept. 30, 1975

236,978

SWITCHING EDUCATIONAL BOARD

Charles G. Valentine, Stamford, Conn., assignor to
Xerox Corporation, Stamford, Conn.

Filed Apr. 27, 1973, Ser. No. 355,222

Term of patent 14 years

Int. Cl. D19—07

U.S. Cl. D19—62

FIG. 2

FIG. 1 is a left perspective view of a switching educational board showing my new design; and

FIG. 2 is a right perspective view thereof.

The rear of the switching educational board not shown is plain and unornamented.

I claim:

The ornamental design of a switching educational board, substantially as shown and described.
